(57) **CLAIM**

The ornamental design for a flashlamp for photography, as shown and described.

DESCRIPTION

FIG. 1 is a perspective view of the flashlamp for photography according to my invention;

FIG. 2 is a front view thereof;

FIG. 3 is a top view thereof;

FIG. 4 is a left view thereof;

FIG. 5 is a right view thereof;

FIG. 6 is a bottom view thereof; and,

FIG. 7 is a back view thereof.

The broken line disclosure represents unclaimed portions of the flashlamp.
